LOAD STABILIZING MEANS FOR
MODULATION SYSTEMSGomer L. Davies, Woodside, Md., assignor to
Washington Institute of Technology, Inc.,
Washington, D. C., a corporation of Delaware

Application October 14, 1938, Serial No. 235,079

2 Claims. (Cl. 179—171.5)

This invention relates generally to systems and devices for modulating radio frequency energy and, more particularly, to systems in which energy modulated at different frequencies is supplied to 5 separate loads.

In the operation of systems of the type referred to differently-modulated energy may be supplied to two antennas for the purpose of radiating two differently modulated fields which overlap to provide an equi-signal zone which may be used as a 10 guidance beacon for aircraft. If the two radiated fields are characterized by different modulation frequencies, it is usual practise to supply each of the two radiating antennas with radio frequency 15 energy from a common source, modulating means being interposed between the source and each antenna and being generally of the type known as mechanical modulators.

It has been found that in such systems the 20 energizing current in each of the antennas will vary from zero to a maximum, such variation being at the modulating frequency. This variation of the power in the load will cause regulation in the tank circuit supplying the antennas, such 25 regulation being also at the modulating frequency. Inasmuch as the second antenna is supplied with radio frequency energy from the source modulated at a second frequency, it will be apparent that regulation will also occur in the input circuit at 30 this second frequency. Thus, the energy supplied to each antenna is modulated not only at the intended frequency but also, and due to the regulation in the input circuit due to the modulation of the energy supplied to the other antenna, 35 at the modulation frequency of the energy supplied to the other antenna. This effect is known as cross-modulation and in order to decrease or do away with this effect it is the usual practise to operate the system at a low fraction of its possible 40 output in order to increase the ratio of the power in the input circuit to the power drawn by the antennas.

I have found that such cross-modulation may be effectively decreased or entirely prevented by 45 providing with each antenna a non-radiating load which is supplied with power in a varying amount which is equal at any time to the difference between the maximum load current drawn by the associated antenna and the instantaneous value 50 of the current drawn by the antenna. Thus, the dummy load will be connected with the modulator in such a manner that, when the full power of the input circuit is supplied to the antenna, no power is supplied to the dummy load, this ratio then 55 changing constantly through equality until full

power is drawn by the dummy load and no power is drawn by the antenna. Thus, while the output of each modulator will be supplied to an antenna and to a dummy load, the power supplied to each modulator will be constant and variations in the 5 antenna loads will not be reflected back into the input circuit. I have found that if the load on the source of power is made constant in this manner the entire possible power output of the source may be more nearly employed.

In prior art systems, in which means according to this invention are not employed, and in which the maximum power required to be supplied to each antenna is, for example, 50 watts, (33 1/3 watts carrier, 100% modulated) it has been necessary 10 to provide a source having a possible power output of approximately 400 watts, the excess, or 300 watts, providing no useful purpose but being necessary in order to maintain the required large ratio of power in the input circuit to power in the 15 load circuit. In systems employing the present invention it is, of course, not possible to utilize the entire power of the source in the antennas due to the power absorbed by the dummy loads, but the maintenance of a constant load on the source 20 permits a much larger fraction of the power of the source to be applied to the useful loads.

It is, accordingly, the object of the invention to provide an electrical system for supplying modulated radio frequency energy from a source to 30 two or more loads, such as antennas, which system will include means for maintaining a constant load on the source of power, thus preventing cross-modulation.

Other objects and features of novelty will be 35 apparent from the following description and the appended drawing, it being understood, however, that such description and drawing are only illustrative of the invention, which is not limited in any way thereby or otherwise than by the appended claims.

The single figure of the drawing is a circuit diagram illustrating a beacon system incorporating means according to the invention.

In the single figure of the drawing there is illustrated a beacon system employing the load stabilizing means of the present invention. In this system a tank circuit 1, which forms the final stage of a source of radio frequency energy, is connected to supply energy to two useful loads 2, 3 which may be antennas adapted to radiate fields which overlap to provide an equi-signal zone which may be used as a guidance means for aircraft. The output coil 4 of the tank circuit is 50 55 60 65 70 75 80 85 90 95 100

coupled to two coils 5, 6. Each of these coils is connected to supply energy to one of the useful loads, modulating means being connected between each of such coils and associated useful load in order that the radio frequency energy in each such useful load will be modulated at a characteristic frequency.

One of the output terminals of coil 5 is connected to two shielded transmission lines 10, 11 and the second terminal of the coil is grounded at 12 through the shields of the two lines. The line 11 is connected to supply current to the useful load 2, while the second transmission line 10 is connected to supply current to a dummy load 13 the purpose of which will be made apparent hereinafter.

Mechanical modulating means are connected in the transmission lines 10, 11 in order to impress a characteristic modulation on the radio frequency energy supplied to the two loads. Such means comprise a rotary capacitor including the two stator plates 14, 15, which are connected, respectively, to the transmission lines 10, 11 by shielded transmission lines 16, 17, and a rotor 18 which is grounded at 19 and which has plates at the opposite ends thereof which pass over the stator plates as the rotor is operated. Short-circuited tuning stubs 20, 21 are also connected to transmission lines 10, 11 and provide means for controlling the reactance at the point of connection of the modulating means to the transmission lines when a condition of maximum impedance obtains at that point. It will be seen that the movement of the rotor will cause the plates thereof to pass the two stator plates and alternately and progressively short-circuit the two transmission lines to ground at 19 through these stator plates.

In the operation of the modulator 14, 15, 18, when the rotor is in the position illustrated, with the one plate thereof entirely covering the stator plate 14, transmission line 11 will be short-circuited to ground at 19 and will not pass any current to the load 2. At the same time current will flow from coil 5 through transmission line 10 directly to load 13, the modulator not drawing any current from line 10 at this time. As the rotor 18 continues its movement, the one plate thereof will pass away from stator plate 14, thereby causing an increasing amount of current to be drawn through line 11 to the useful load 2, while the other plate thereof will progressively cover the stator plate 15, thereby progressively short-circuiting the transmission line 10 and reducing the power supplied to the dummy load. The proportioning and positioning of the stator and rotor plates is preferably such that a constant amount of current will be drawn by the modulator and supplied by it to the useful and dummy loads, whereby the total power supplied to the two loads will be constant. In other words, as the modulator supplies a progressively increasing amount of power to the dummy load, a progressively decreasing amount of power will be supplied to the useful load.

It will be seen that the radio frequency energy output of the source will be supplied to the useful and passive loads in amounts which will vary in accordance with the size and positioning of the stator and rotor plates and that the frequency of the supply of maximum or minimum current to either of the loads will be determined by the speed of the rotor and the number of the rotor and stator plates. The two loads will therefore

be supplied with current at the same radio frequency, modulated equally but with opposite sign, whereby the total power supplied to the two loads will remain substantially constant.

A dummy load 30 is associated with load 3 in the same manner as described hereinbefore with respect to dummy load 13 and useful load 2, and radio frequency energy is supplied to these two loads through transmission lines 31, 32, respectively. Tuning stubs 33, 34 are connected to the transmission lines for a purpose which is identical with that of stubs 20, 21. Modulating means comprising a rotary capacitor including the stator plates 35, 36 and the rotor 37 are provided and are operable, in the same manner as the means described hereinbefore, to vary the power supplied to the two loads 3 and 30 in such a manner that the power supplied to the passive load 30 at any instant will be equal to the difference between the maximum amount of power drawn by the useful load 3 and the instantaneous power drawn by the load 3, whereby the total power supplied to the two loads remains constant. In order to modulate the energy supplied to useful load 3 at a characteristic frequency different from the modulation frequency of the energy supplied to load 2, the rotor 37 may be constructed in the same manner as rotor 18 and driven at a different speed, or, as illustrated in the drawing, it may be provided with three or more plates and, accordingly, may be driven at the same speed as the rotor 18.

It will be seen that, by the provision of the dummy loads and by the energization of each of these in such a manner that the power supplied thereto always has the described relation to the power supplied to the associated useful load, the total power drawn by each branch of the system disclosed will be maintained constant and the total power drawn from the source 1 will therefore be constant, whereby it is possible to utilize a greater fraction of the possible output of the source in the useful loads.

While I have illustrated and described one embodiment of my invention, it will be apparent to those skilled in the art that further improvements and modifications thereof may be made without departing in any way from the spirit or scope of the invention, for the limits of which reference must be had to the appended claims.

What I claim is:

1. An electrical system for supplying modulated radio frequency energy to a plurality of useful loads such as antennas, comprising a source of energy, a plurality of useful loads, transmission lines connecting each of said loads to the source, a non-useful load associated with each useful load, transmission lines connecting each of said non-useful loads to the source, means associated with each useful load and its associated non-useful load for modulating the energy supplied thereto and comprising means for alternately and progressively short-circuiting to ground energy from the transmission lines connecting the useful and non-useful loads to the source, in such amounts that the energy supplied to any non-useful load at any instant is approximately equal to the difference between the maximum energy supplied to the associated useful load and the instantaneous energy supplied thereto.

2. An electrical system comprising a source of radio frequency energy, a plurality of useful loads such as antennas connected thereto, means

for differently varying the amounts of energy supplied by said source to said useful loads, a plurality of non-useful loads each of which is associated with one of said useful loads and is connected to the source, means for varying the amount of energy supplied to each of said non-useful loads, the means for varying the energy supplied to each useful load and to its associated non-useful load comprising spaced conducting members connected respectively to the connections between the source and the useful load and

the source and the non-useful load, and grounded conducting means movable progressively and successively into capacitative relation with said conducting members to thereby progressively and successively short circuit energy from said useful and non-useful loads to ground, whereby the total energy supplied by the source to the useful and non-useful loads remains substantially constant.
